UNITED STATES PATENT OFFICE.

LYMAN A. WILSON, OF NEW YORK, N. Y.

ENDLESS-FILM REEL.

Application filed September 2, 1922. Serial No. 585,914.

This invention relates to an endless film reel, and is an improvement of my endless film reel described in my Patent No. 1,382,040, dated June 21st, 1921.

5 Its object is the production of a reel, by means of which a spirally wound endless film can be unwound at its core in amounts equal to that simultaneously wound on the outside thereof. The second object of the 10 invention is the production of a reel that is wound up with outer windings and unwound at its core without injury thereto.

In the drawing Fig. 1 represents an elevation of an exemplification of the endless 15 film reel; Fig. 2 shows a top plan view of Fig. 1; Fig. 3 indicates an enlarged partial section of Fig. 2 on the line 3, 3 and partial side view of some of the parts of the reel; Fig. 4 represents an enlarged section of Fig. 20 2 on the line 4, 4 and Fig. 5 is a fragmentary plan view of Fig. 4.

A casing is indicated in its entirety by the letter A, and comprises the front wall 20, the rear wall 21, the side walls 22 and 23, 25 bottom wall 24 and the detachable cover 25, with the sleeve 25^a.

A lower supporting frame is designated in its entirety by the letter B, and comprises a central supporting disc 28 from which 30 extend the straight arms 29, that join with the inclined members 30, and the latter have formed therewith the feet 31. An upper supporting frame is indicated in its entirety by the letter C, and comprises the central 35 supporting disc 35, that has extending therefrom the sleeve 36. A thread 37 is formed in the said disc 35 and in the sleeve 36. Straight arms 38 extend from the disc 35, and inclined members 39 with the feet 40, 40 extend from the arms 38. Screws 41 extend through openings on the feet 31 and 40 and detachably clamp them to the cover 25.

A turntable is indicated in its entirety by the letter D. The turntable comprises the 45 upper annular supporting disc 43 with the annular depression 44. A cup shaped barrel extends from the disc 43 and comprises the side wall 45, that extends from the bottom wall 46.

50 A sleeve 47 extends from the wall 46, and a horizontal extension 48 is formed with the sleeve 47. The sleeve 47 is journaled in the sleeve 25^a. A bushing 52 is axially supported in the sleeve 47. An annular disc 53 is located in the annular depression 44, and is detachably secured in

place to the turntable D, by means of the screws 54.

An annular disc 58 with one member 59 of a ball race is fastened to the disc 35, and 60 the second member 60 of the ball race is formed in the lower face of the sleeve 47. Ball bearings 61 are located in the members of the ball race to support the sleeve 47.

A stationary cup shaped gear housing is 65 indicated in its entirety by the letter E. The housing E comprises the cylindrical wall 64, with the flange 65 at its upper end and the flat wall 66 at its bottom end. A sleeve 67 extends from the wall 66 and has 70 formed therewith the threaded shank 68, that is in threaded engagement with the sleeve 36. A bushing 69 is fastened to the sleeve 67. A cover 70 is detachably supported on the flange 65 and is secured in place by means of the screws 71. A sleeve 72 extends from the cover in the axial center thereof and a bushing 73 is provided for the sleeve 72. A plurality of sleeves 78 with their axial centers in the path of a circle 75 extend from the cover 70, and are each provided with bushings 79.

An internal gear is indicated in its entirety by the letter G and comprises the cylindrical wall 80 with the teeth 81, and from 85 which extends the flat bottom wall 82. An axial sleeve 83 extends up from the wall 82.

A bearing 86 is supported on the disc 28 and is provided with the bushing 87 and ball bearing 88.

A main shaft 92 is fastened to the sleeve 83 of the internal gear G and is journaled in the bushings 73, 69 and 87. The bottom end of the shaft 92 bears on the ball bearing 88.

90 Spindles 93 are journaled in each of the bushings 79 and have fastened to their upper ends the guide rollers 95 sometimes curved on their outer faces. Spur gears 96 are fastened to the lower ends of the 100 spindles 93 and mesh with the teeth 81 of the internal gear G.

A worm wheel 97 is fastened to the main shaft 92 and a worm wheel 98 is fastened to the sleeve 47.

105 A stuffing box is indicated in its entirety by the letter H. The said stuffing box comprises the sleeve 99 with the flange 100. The flange 100 is detachably fastened to the wall 20 of the casing A and the sleeve 99 extends through an opening in said wall 20 into the said casing A. A gland 101

and packing 102 of the usual construction are provided for the stuffing box H.

A frame is indicated in its entirety by the letter I and comprises the vertical member 103 with the upper foot 104 and the lower foot 105. Journal bearings 106, 107 and the boss 108 are formed with the vertical member 103. The foot 104 is detachably fastened to the cover 25 and the foot 105 is detachably fastened to one of the arms 29. A journal bracket 110 with the vertical legs 111 is fastened to and extends up from one of the arms 38 and a journal bracket 112 with the vertical legs 113 is fastened to and extends from the bottom face of said arm 38.

A driving shaft 116 extends through the stuffing box H into the casing A and is journaled in the journal bearing 106 and in the legs 111. A worm 117 is fastened to the shaft 116 between the legs 111 and meshes with the worm wheel 98. A spur gear 118 is fastened to the shaft 116. A second shaft 122 is journaled in the journal bearing 107 and in the legs 113. A worm 123 is fastened to the second shaft 122 between the legs 113, and meshes with the worm wheel 97. A spur gear 124 is fastened to the shaft 122. A shaft 125 is fastened to and extends from the boss 108. An idler spur gear 126 is journaled on the shaft 125 and meshes with the spur gears 118 and 124.

A guide cover plate is indicated in its entirety by the letter J and has formed therewith the lug 128 and the bifurcated lugs 129. A hinge bracket 134 with the hinge member 135 is fastened to and extends up from the cover 25. A second hinge member 136 is fastened to the cover plate J and is hinged to the member 135, by means of the hinge pin 137. Posts 138 with threaded shanks 139 are fastened to and extend up from the cover 25. The shanks 139 are positioned to extend through the bifurcated lugs 129, and nuts 140 for said shanks 139 hold the plate J in place.

A sleeve post 144 extends up from the cover 25 and adjustably supports the spindle 145, which latter has fastened to its upper end the film guide rod 146. The latter has formed therewith the film guide loop 147.

A sleeve post 150 extends up from the cover 25, and has adjustably supported therein the spindle 151 with the hexagon head 152. Springs 153 and 154 extend from one of the faces of the hexagon head 152 and have respectively journaled to their swinging ends, the tension guide rollers 155 and 156.

A post 160 extends up from the cover 25, and has journaled thereto the guide roller 161. A spindle 162 extends from the lower face of the lug 128 and has journaled thereto the guide roller 163.

An endless film is indicated in its entirety by the letter K and leads in a vertical plane

or a plane perpendicular to the turntable D from a motion picture machine or other apparatus, not shown, for which it is to be used.

The film K extends around the guide roller 163 and is wound around the guide rollers 95 in a plurality of windings K'. The innermost winding leads around one of the guide rollers 95 as indicated at K². The film K then rises and twists or makes a turn of ninety degrees to a horizontal plane as indicated at K³ and is lead through the film guide loop 147. After leaving the guide loop 147 it extends around the guide roller 161 and in so doing is twisted back to a vertical plane as indicated at K⁴, and returns to the motion picture apparatus or other apparatus for which it is used.

The guide tension rollers 155 and 156 bear against the outermost winding K⁵ to maintain the film in proper position on the turntable D. The spindle 151 can be located in different angular positions to regulate the pressure of the rollers 155 and 156 against the film. The casing A contains a liquid lubricant to lubricate the moving parts of the machine therein and is indicated by the line A'.

To operate the endless film reel the driving shaft 116 is turned by means not shown, and the second shaft 122 is thereby turned through the idler spur gear 126 in the same direction. The shaft 116 through the worm 117 turns the worm wheel 98 and the shaft 122 through the worm wheel 97 turns the main shaft 92. The turn table D turns with the worm wheel 98 in the direction of the arrow M, and the gear housing G remains stationary. The annular disc extension 53 extends inwardly beyond the outer face of the guide rollers 95, and thereby the endless film K is prevented from entering the clearance space N between the inner edge of said extension 53 and the outer edge of the cover 70 of the gear housing E. The main shaft 92 turns with the worm wheel 97 and thereby the internal gear G also turns in the direction of the arrow M. The spur gears 96 simultaneously turn in the direction of the arrows O when the gear G turns in the direction of the arrow M.

The diameters of the worm wheels 97, 98, the internal gear G, the spur gears 96, 118, 124 and the guide rollers 95 are proportioned so that the winding K⁶ at the core of the film K is forced through the film guide loop 147 at the same rate of rectilinear speed as the circumferential speed of the outermost winding K⁷ of the endless film K. Thereby the tension of the film at its outer and inner windings is equalized and the film is evenly wound and unwound during its operation.

It is to be noted that the driving mechanism of the film reel is supported by the

frames C and B, which extend from the cover 25 of the housing A. When the cover is removed the said mechanism can be easily examined. The opening 101^a in the wall 20 of the casing A is made of large diameter to allow the shaft 116 which only extends a short distance out of the casing A to be moved through the said opening 101^a when the cover 25 is tipped and removed from the 10 casing.

Various modifications may be made in the invention without departing from the spirit thereof and the present exemplification is to be taken as illustrative and not limitative 15 thereof.

Having described my invention what I desire to secure by Letters Patent and claim is:—

1. In an endless film reel the combination 20 of a rotating turntable having formed therewith an annular supporting disc, an annular disc extension extending from the inner edge of the supporting disc and detachably connected to the turntable, a stationary element within the said annular disc extension and rotating guide rollers extending above said element.

2. In an endless film reel the combination 30 of a casing, a detachable cover for the casing, a pair of frames extending from said cover into the casing, a turntable with an annular supporting disc above said cover, a cup shaped barrel in the turntable depending from its annular supporting disc, a sleeve 35 coaxial with the barrel and extending from the bottom wall thereof, the bottom end of said sleeve rotatably supported on one of said frames, means to turn said sleeve, a stationary cup shaped gear housing within the 40 cup shaped barrel, a cover for the gear housing, a sleeve extending from the bottom wall of the gear housing fastened to the latter frame, a bearing supported on the other frame, a main shaft with its bottom end 45 supported in said bearing and its upper end extending into the gear housing and journaled into the cover thereof, means to turn said shaft, an internal gear in the gear hous-

ing and fastened to said shaft, a plurality of spindles journaled in the cover of the gear 50 housing, a spur gear fastened to the lower end of each of said spindles meshing with said internal gear, a guide roller fastened to each of said spindles above said cover and means to turn the turntable. 55

3. In an endless film reel the combination of a casing, a detachable cover for the casing, a pair of frames extending from the lower face of the cover into said casing, a cup shaped turntable with its lower end rotatably supported on one of said frames, a stationary gear housing located within the turntable and fastened to the latter frame, guide rollers over the gear housing, means to turn the guide roller with its lower end 60 supported on the second frame and means to turn the turntable. 65

4. In an endless film reel the combination of a casing, a detachable cover for the casing, a pair of frames extending from the lower face of the cover into said casing, a cup shaped turntable, a sleeve at the bottom end of the turntable rotatably supported on one of said frames, a worm wheel fastened to said sleeve, a cup shaped gear housing 70 within the cup shaped turntable, a sleeve extending from the gear housing through the sleeve of the turntable and supported on said frame, a main shaft journaled in the latter sleeve with its lower end 75 supported by the second frame and its upper end extending into the gear housing, a gear in the gear housing fastened to said shaft, guide rollers journaled above the cover of the gear housing, rotating means between 80 said guide rollers and said gear, a worm wheel fastened to said shaft, a worm meshing with each worm wheel, a driving shaft for one of said worms, a shaft for the second 85 worm and connections between the shafts of the worms. 90

Signed at the borough of Manhattan, city of New York in the county of New York and State of New York this 15th day of August A. D. 1922.

LYMAN A. WILSON.
